UNITED STATES PATENT OFFICE

164,466

BOTTLE CARRIER

Edwin L. Arneson, Morris, Ill.

Application December 9, 1948, Serial No. 150,056

Term of patent 14 years

(Cl. D58—13)

To all whom it may concern:

Be it known that I, Edwin L. Arneson, a citizen of the United States, residing at Morris, in the county of Grundy and State of Illinois, have invented a new, original, and ornamental Design for a Bottle Carrier, of which the following is a specification, reference being had to the accompanying drawing, forming a part hereof.

In the drawing:

Fig. 1 is a perspective view of the bottle carrier, showing my new design;

Fig. 2 is a side elevational view;

Fig. 3 is an end elevational view; and

Fig. 4 is a top plan view.

I claim:

The ornamental design for a bottle carrier, substantially as shown.

EDWIN L. ARNESON.
